United States Patent Office

Des. 222,533
Patented Nov. 2, 1971

222,533

TRACTOR BODY

Leo J. Lorenz, Farmington, and Wilford E. Bean, Southfield, Mich., assignors to Massey-Ferguson Inc., Detroit, Mich.

Filed Aug. 21, 1970, Ser. No. 24,624

Term of patent 14 years

Int. Cl. D12—09

U.S. Cl. D14—3

Fig. 1

Fig. 2

Fig. 3

Fig. 4

FIG. 1 is a perspective view of a tractor body embodying our new design and taken from the left side thereof;

FIG. 2 is a perspective view of a tractor body taken from the right side thereof;

FIG. 3 is a perspective view of a tractor body taken generally from the front and left side thereof; and

FIG. 4 is a perspective view of a tractor body taken generally from the rear and left side thereof.

We claim:

The ornamental design for a tractor body, substantially as shown.
